UNITED STATES PATENT OFFICE.

JOHN W. BARTLETT, OF MOLINE, ILLINOIS.

GANG-PLOW.

SPECIFICATION forming part of Letters Patent No. 310,775, dated January 13, 1885.

Application filed January 26, 1884. (No model.)

To all whom it may concern:

Be it known that I, J. W. BARTLETT, of Moline, in the county of Rock Island and State of Illinois, have invented certain new and useful Improvements in Gang-Plows; and I do hereby declare the following to be a full, clear, and exact description of the invention, such as will enable others skilled in the art to which it appertains to make and use the same.

10 My invention relates to an improvement in gang-plows. The plows of this character which have hitherto been made are objectionable on account of the great draft required to move them and the difficulty with which the 15 points of the plows are held in the exact vertical adjustment required for different depths of furrow.

The object of my present invention is to overcome these objectionable features and furnish a light-draft gang-plow which shall do its work effectively and can be controlled by the driver with the greatest convenience and precision.

20 With these ends in view my invention consists in certain features of construction and combinations of parts, as will be fully described, and pointed out in the claims.

In the accompanying drawings, Figure 1 is a side view. Fig. 2 is a side view. Fig. 3 is 30 a plan view, and Figs. 4 and 5 are detached views.

The main frame, when two plows form the gang, consists, essentially, of the three parts a , a' , and a'' , constructed of suitable material, 35 and firmly fastened together. Each of the parts a and a' is preferably constructed of two flat iron rails separated by blocks, to form long vertical slots, which serve to keep the plow standards from horizontal displacement. The 40 depending bracket B , consisting of the main arm b and the bracing-arm b' , is rigidly secured to the part a' of the main frame. To the lower end of the main arm b the heel of the landside of the plow C is pivoted. The bracket B is 45 provided with the laterally-extending stud b' , which forms an axle for the wheel D . The circumference of the wheel D extends a little below the foot of the plow C , and serves to bear the weight of this plow and a portion of the 50 main frame when allowed to rest on the ground. The standard of the plow C extends upward through the long vertical slot in the part a' of

the main frame. The depending bracket E is constructed in a similar manner to the bracket B , just described, to the lower end of the main arm of which is pivoted the heel of the landside of the plow C . The curved lever F has one end pivoted to the bracket E , as shown, and provided with a laterally-extending stud, e' , which forms an axle for the wheel D' . The outer end of the lever F extends forward and terminates in a handle within the convenient reach of the driver. This lever F is locked in the required positions by resting upon a lug, a' , on the rigid standard a' when raised, and in the slot a'' , formed in the rear of the main frame when depressed. The standard of the plow C extends upward through the long vertical slot in the part a' of the main frame. The axle G is journaled in boxes suitable for the purpose, secured to the rear portion of the main frame, and is bent to form a crank at one end on which the large wheel D is mounted, and is provided with an arm, g , at the other. The rocking shaft H has one end journaled at 75 or near the center of the semicircular toothed sector K and the other in the adjustable bracket k , the latter being secured to the part a' of the main frame. The toothed sector K is pivoted below its center to the part a' of the main frame at x , and is provided with curved slots k' in the ends of its rim. Through these slots and the part a' of the main frame the bolts k'' pass, and are tightened and loosened by nuts. By means of these slots and bolts the sector K 80 is adjustable in a limited rotary motion about the pivot x . The rocking shaft H is provided with the arms h and h' —one at each end—and with the lever L and toothed sector l , all secured to the shaft in such a manner as to turn 85 with it. The end of the arm h is connected with the upper end of the standard of C by means of an adjustable swivel and pivoted links M . The end of the arm h' is connected with the upper end of the standard of C by 90 the straight link N , pivoted thereto. The lever L is situated within convenient reach of the driver, and is provided with a spring-depressed dog, o , situated in a position to engage the teeth of the sector K , and a short lever, o' , pivoted to the lever L near the handle, and adapted to be operated by the hand simultaneously with the lever L . The action of the lever o' is conveyed to the spring-depressed 95 100

dog o by the connecting-rod o^2 . The lever P is mounted loosely on the rocking shaft H , and is connected with the arm g by the pitman g' , pivoted to the end of the arm g and 5 to the lever P a short distance from the shaft H . The lever P is provided with a spring-depressed dog adapted to engage the sector l , and hand-lever and connecting-rod in every respect similar to those just described in connection with the lever L . The colter-wheels 10 are journaled in the curved yokes r . These yokes are swiveled to the clips r' , which are removably secured to the parts a and a' of the main frame by bolts r^2 , provided with suitable 15 nuts, r^3 , said bolts passing through the parts a and a' of the main frame and the side of the clips. The driver's seat y is mounted on the curved band-spring y' , secured to the rear part of the main frame. z is the foot-rest. The 20 front end of the main frame is supported by the wheel D^3 , mounted on the crank-shaped axle S . This axle S terminates in a section of the fifth-wheel s , upon which a similar section, s' , secured to the forward end of the main 25 frame rests, and is secured thereto by the king-bolt t . The king-bolt t extends through the fifth-wheel s sufficiently far, or is made sufficiently long to pass through a socket, u , in the rear end of the clevis U . The latter terminates in two 30 forwardly-extending arms, each of which is provided with a vertical socket, u' , at its extremity. A plate, V , terminating rearwardly in a sleeve, v , and forwardly in a perforated bar, v' , is hinged vertically between the arms 35 of the clevis by a bolt, v^2 , passing through the sockets u' and the sleeve v . An adjustable connecting-link, W , terminates rearwardly in two laterally-perforated chucks, w , the latter being adapted to embrace the perforated 40 bar v' . A bolt, w' , is constructed to pass through the perforations in the chucks w and bar v' , and thereby lock the link W in vertical adjustment. A flat curved perforated bar or brace, Y , is constructed at one end to embrace 45 the crank-axle S , while the perforated portion rests on the lower arm of the clevis U , and is constructed to be locked thereto in lateral adjustment by a bolt, y^2 , which passes through a perforation in Y and the perforation y' in the 50 lower arm of the clevis. The object of this adjustable brace Y is to lock the axle in a position a little in advance of a perpendicular to the furrow-line. When the draft is applied, the wheel D^3 will now spring back to its proper 55 position, and the plows will be held steadily up to the land. The series of perforations in Y enables the operator to advance the wheel D^3 more or less as the soil to be broken is heavier or lighter. 60 The plow is operated as follows: The sector K and adjustable swivel M are adjusted in such a position that when the levers L and P are vertical, or nearly so, and the lever F thrown forward, the plows will turn a furrow six inches 65 deep. The notches on the toothed sector K are constructed at such a distance apart that the movement of the lever L one notch in

either direction will throw the points of both plows either down or up a sufficient distance to make the furrow an inch deeper or shallower, 70 as may be desired. By means of the adjustable toothed sector K and the lever L the depth of the furrow may be determined to the fractional part an inch. It will be noticed, furthermore, that the same motion of the lever which raises 75 or lowers the points of the plows will depress or elevate the large wheel D^2 by rotating the axle G .

Whenever it is desired to raise or lower the wheel D^2 without disturbing the elevation of 80 the points, it is accomplished by moving the lever P backward or forward, and locking it in any required position by the spring-depressed dog in contact with the toothed sector l .

When it is desired to turn the plow at the 85 end of a furrow or elsewhere, or when going to or coming from the field, the plow is readily thrown upon three wheels by moving the lever L to the rear and pulling upward and backward upon the lever F , the plows and wheel D being by these motions raised from the ground. The number of plows is not limited to two, but may by the same principle of construction be increased to any number required.

It is evident that slight changes may be made 95 in the form and construction of the several parts of my gang-plow without departing from the spirit and scope of my invention. I do not desire, therefore, to limit myself strictly to the construction herein set forth.

I am aware that it is not new to construct a ground-wheel to follow and support the weight of a plow, and I do not claim such, broadly; but

What I claim as new, and desire to secure by Letters Patent, is—

1. In a gang-plow, the combination, with a main frame supported on wheels, and a crank-axle journaled in the main frame and provided with a supporting-wheel, of two or more plows pivotally connected to arms depending from the main frame, a rock-shaft journaled in bearings mounted on the main frame, a hand-lever rigidly secured to said rock-shaft, a hand-lever loosely sleeved on said rock-shaft, sector-bars for each hand-lever, and links for transmitting the motion of the hand-levers to the main frame and plows, substantially as set forth.

2. The combination, with the main frame 120 and a plow pivotally connected at the heel of its landside, with a stationary depending arm attached to the main frame, of an adjustable toothed sector, a rock-shaft and link, and a hand-lever for raising and lowering the point 125 of the plow, substantially as set forth.

3. The combination, with the main frame and a series of plows, each being pivotally connected at the heel portion of its landside with a stationary depending arm attached to the main 130 frame, of an adjustable toothed sector, a rock-shaft, connecting-links, and a hand-lever for simultaneously raising or lowering the points of the several plows, substantially as set forth,

4. The combination, with a main frame and plow vertically adjustable on said frame, of a lever pivotally connected to the frame, and a furrow-wheel journaled to said lever, substantially as set forth. 35
5. The combination, with a main frame and plow vertically adjustable on said frame, of the bent lever F, pivotally connected to the main frame in rear of the plow, and a furrow-wheel journaled to said lever. 10
6. The combination, with a main frame and a plow vertically adjustable on said frame, of a lever pivotally connected to said frame, a furrow-wheel journaled to said lever, and a 15 stud or projection on the main frame for holding the furrow-wheel in its depressed adjustment.
7. The combination, with a plow-frame, of a crank-axle having a land-wheel thereon, a 20 lever for turning said axle, and a lever pivoted to said frame, and a furrow-wheel journaled to said lever.
8. In a gang-plow, the combination, with a 25 wheel for supporting the forward end of the frame, of independently-adjustable wheels for supporting the rear end of the frame, and a non-adjustable wheel connected with the main frame between the front and rear wheels, substantially as set forth. 50
- 30 9. The combination, with a plow pivotally connected at the heel of its landside to the frame of the machine, and a plow-standard terminating above the frame, of the rock-shaft, a link connecting the plow-standard and rock-shaft, and a hand-lever and sector for securing the rock-shaft in any desired adjustment. 55
10. In a gang-plow, the combination, with a frame, a crank-axle journaled in the frame, and provided with an arm, and a wheel journaled 40 on the crank-axle, of a rock-shaft, a lever loosely mounted on a shaft, a sector rigidly secured to the shaft, devices for locking the lever to the sector, a pitman connecting the lever and arm, a lever rigidly secured to said 45 rock-shaft, and a sector rigidly secured to the frame, substantially as set forth.
11. The combination, with a main frame, brackets depending from the frame, plows pivoted at their heels to said brackets, and 50 devices for elevating the points of said plows, of a furrow-wheel journaled on a non-adjustable stud secured to one of said brackets, and a lever pivoted to another of said brackets, and a furrow-wheel journaled to said lever, 55 all of the above parts combined as described.
- In testimony whereof I have signed this specification in the presence of two subscribing witnesses.
